(57) **CLAIM**

The ornamental design for a loudspeaker as shown and described.

DESCRIPTION

FIG. 1 is a top plan view of a loudspeaker showing the new design;

FIG. 2 is a side elevational view thereof;

FIG. 3 is an opposite side elevational view thereof;

FIG. 4 is a rear elevational view thereof;

FIG. 5 is a front elevational view thereof;

FIG. 6 is a bottom plan view thereof; and,

FIG. 7 is an enlarged partial view of area 7 in FIG. 1.

The evenly spaced broken lines illustrate portions of the loudspeaker that form no part of the claimed design. The dash-dot broken lines in FIGS. 1 and 7 illustrate enlarged partial view indicators and form no part of the claimed design.

1 Claim, 5 Drawing Sheets
